LOCK

Charles Kemp, New York, N. Y., assignor to Kemp Lock, Inc., New York, N. Y., a corporation of New York

Application July 26, 1934, Serial No. 736,986

8 Claims. (Cl. 70—14)

This invention relates to locks. It is particularly directed to a lock having bolts movable in transverse directions.

An object of this invention is to provide a compact and rugged lock of the character described, which shall be relatively inexpensive to manufacture, comprise comparatively few and simple parts, be smooth and positive in operation and withal practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a plan view of a lock embodying the invention attached to a door;

Fig. 2 is an elevational, inside view of the lock with part of the cover broken away to show the interior construction and showing the parts in fully locked position;

Fig. 3 is a cross-sectional view taken on line 3—3 of Fig. 2;

Fig. 4 is an elevational inside view of the lock shown in Fig. 2 with parts removed, and showing the lock in open position;

Fig. 5 is a view somewhat similar to Fig. 4 but illustrating the parts with the main bolt partly projected; and

Fig. 6 is a cross-sectional view taken on line 6—6 of Fig. 5.

Fig. 7 is a section of Fig. 4 taken on line 1—1 looking in the direction of the arrows.

Referring now in detail to the drawing, 10 designates a door and 11 a door jamb. Fixed to the door 10 is a lock 12 embodying the invention and cooperating with the keeper 13 fixed to the door jamb 11. The door 10 is provided with the usual opening 14 to receive the key tumbler 15, the same being attached to a location plate 16 contacting the inside of the door.

Attached to the door and fitted over the location plate is the lock casing 17 having a front wall 18 parallel to the door and an end wall 19 flush with the edge of said door. The inner surface of the casing wall 18 is formed with a pair of parallel guides 22 on which there is slidably mounted the main bolt 23 adapted to project through the opening 24 in the end wall 19.

Slidably mounted on the main bolt 23 for movement in a direction transverse to the movement of said bolt is a slider 25 to which there is attached a tubular member 26 having a semi-cylindrical portion 26a at one end. Mounted on the casing wall 18 is a knob 28 to which is attached an arm 29 disposed within the casing and having at the outer end thereof a pin 30 engaging within the tubular member 26.

Closing the rear of the casing and fixed thereto is a rear cover plate 33 on which there is rotatably mounted a cup-shaped member 34 having a slot 35 through which there extends the key actuated strip 36. Attached to the member 34 is an arm 38 having at the end thereof a pin 39 received within the semi-cylindrical portion 26a of tubular member 26.

It will now be understood that the main bolt may be projected either by turning the knob 28 or by the key mechanism 15, 36. A torsion spring 20 wound around a pin 41 fixed to the slider 25, is provided with outer ends 43 and 44 engaging the tubular member 26 and a portion of the main bolt, respectively, for retaining the main bolt at the limit of its movement either to projected or retracted position.

The main bolt 23 is preferably of box like formation and provided with a front wall 45 substantially contacting the casing wall 18, top and bottom walls 46 and 47 and an end wall 48. The rear of the bolt may be closed by a cover plate 50 screwed to the bolt in any suitable manner. The wall 45 of the main bolt is formed with a raised L-shaped portion 45a and a depressed corner 45b. The raised portion 45a has a pair of parallel, spaced, horizontal guides 52 and 53 between which there is slidably mounted a bar or member 54 provided with a pair of spaced pins 55, 56. The pin 56 projects on opposite sides of the bar or member 54.

The walls 46 and 47 of the main bolt are formed adjacent the end wall 48 with aligned openings 58 and 59 for the purpose hereinafter appearing. Slidably mounted within said openings and disposed within the main bolt are a pair of aligned, substantially symmetrically disposed, auxiliary bolts 60 and 61. Projecting upwardly from the depressed wall portion 45b is a pin 64 and projecting upwardly from the wall portion 45a is a pin 65 aligned with the pin 64. Pivoted to the pin 64 is a bell crank 66 having a slotted arm 67 engaging the portion of the pin 56 projecting from the bar 54 toward the depressed wall 45b and a second slotted arm 68 received within a slot 69 formed on the inner end of the auxiliary bolt 65.

68 and engaging a transverse pin 70 fixed to said bolt and crossing said slot.

Pivoted on the pin 65 is a bell crank 75 having a slotted arm 71 receiving the portion of the pin 56 projecting toward the cover plate 50 of the main bolt, and a second slotted arm 72 receiving a pin 73 fixed to the inner end of the other auxiliary bolt 61.

Pivoted to the wall portion 45a of the main bolt is a bell crank 75 comprising a plate 76 having a longitudinal groove 77. Secured to the plate 76 and closing the groove is a plate 78 formed with a slot 80 adjacent the end of the slot 77. The plate 76 is formed with a slotted arm 81 engaging the pin 55. Pivotedly mounted within the groove 77 is a member 85 preferably made of wire stock and having a portion 86 received within said groove. Extending from one end of the portion 86 is an arm 87 projecting through the slot 80 and disposed substantially at right angles to said portion 86. Extending from the opposite end of the portion 86 is a bent back portion 88 parallel to said portion 86 and forming a slot therewith. The portions 86 and 88 are preferably in a plane perpendicular to the arm 87.

It will now be understood that upon actuating the arm 87, the member 85 will rotate about the axis of the portion 86. When the arm 87 is moved downwardly, looking at Fig. 4, the bent back portion 88 will be raised and thus be disengaged from the pin 41 on the slider 25. However, when the slider is in the position shown in Fig. 5, movement of the arm 87 upwardly will swing the member 85 about the portion 86 thereof to engage the pin 41.

To actuate the arm 87 for rotating the member 85 the rear cover plate 33 is formed with a slot 90. Said slot has a horizontal portion 91 from which there extends an upwardly inclined portion 92 terminating with a downwardly curved portion 93. The arm 87 projects through the pin 89 in the cover plate and the member 50 of the main bolt is provided with a notch 59a to permit the arm 87 to pass through said slot.

The operation of the lock will now be clear. Beginning with the parts as shown in Fig. 4, the lock is unlocked and the slider 25 is moved upwardly on the main bolt. Upon rotating either the knob 28 or actuating the tumbler 15 with a key to close the lock, the main bolt is projected and the slider moves downwardly with respect to the main bolt to the position shown in Fig. 5. During this movement the pin 41 is not engaged with the portion 88 of the member 85 and the arm 87 moves within the portion 91 of the slot 90 without rotating the member 85. However, when the slider reaches the position shown in Fig. 5, the pin 41 is located between the portions 86 and 88 of the member 85. Further rotation of the knob or key mechanism will cause the slider to begin to move upwardly, further projecting the horizontal or main bolt. Movement of the arm 87, however, within the slot portion 92 will cause the arm to be swung upwardly for rotating the member 85 sufficiently for the portion 88 thereof to engage the pin 41. At this point the horizontal bolt is sufficiently projected to bring the auxiliary bolts 60 and 61 within the keeper 13. During further projection of the main bolt, the slider moves upwardly and due to the engagement of the pin 41 with the member 85 the bell crank 75 is rotated in a clock-wise direction, looking at Fig. 4, to move the sliding bar 54 to the right. Such movement of the bar

54 will cause pivotal movement of the bell cranks 66 and 70 for projecting the auxiliary bolts 60 and 61 outwardly in opposite directions into engagement with the keeper 13, as illustrated in Fig. 2 of the drawing.

At the outer end of the projecting movement of the horizontal bolt the arm 87 enters the portion 93 of the slot and is moved downwardly to quickly disengage the member 85 from the pin 41. However, when the horizontal bolt is retracted the arm 87 moving in the slotted portion 93 in the reverse direction, rotates the member 85 into engagement with the pin 41. Downward movement of the slider 25 with the pin 41 engaging the member 85 causes rotation of the bell crank 75 in a counter-clockwise direction for retracting the auxiliary bolts 60 and 61 during the initial retracting movement of the main bolt. After the auxiliary bolts have been retracted, the member 85 is disengaged from the pin 41 due to movement of the arm 87 into the slot portion 92. During the remainder of the retraction of the main or horizontal bolt, the bell crank 75 does not move and the auxiliary bolts 60 and 61 likewise do not move but are carried with the main bolt.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing, is to be interpreted as illustrative and not in a limiting sense.

Having thus described my invention, I claim as new and desire to secure by Letters Patent:

1. In a lock, a casing, a main bolt slidably mounted therein, means for projecting the main bolt, comprising a slider slidably mounted on the main bolt for movement in a direction transverse to the movement of the main bolt, a member rotatable on the casing and pivotally engaging said slider, an auxiliary bolt slidably mounted on said main bolt for movement in a direction transverse to the movement of the main bolt, a bar slidably mounted on said main bolt for longitudinal movement with respect thereto a bell crank pivoted to said main bolt and having arms engaging said auxiliary bolt and said bar, and a second bell crank pivoted to said main bolt and having an arm engaging said bar, and means for engaging said second bell crank with said slider.

2. In a lock, a casing, a main bolt slidably mounted therein, means for projecting the main bolt, comprising a slider slidably mounted on the main bolt for movement in a direction transverse to the movement of the main bolt, a member rotatable on the casing and pivotally engaging said slider, an auxiliary bolt slidably mounted on said main bolt for movement in a direction transverse to the movement of the main bolt, a bar slidably mounted on said main bolt for longitudinal movement with respect thereto, a bell crank pivoted to said main bolt and having arms engaging said auxiliary bolt and said bar, and a second bell crank pivoted to said main bolt and having an arm engaging said bar, means on said second bell crank adapted to engage said slider, a rear cover plate on said casing, and means on said rear cover plate for controlling said last mentioned means.

3. In a lock, a casing, a main bolt slidably

- mounted therein, means for projecting the main bolt, comprising a slider slidably mounted on the main bolt for movement in a direction transverse to the movement of the main bolt, a member rotatable on the casing and pivotally engaging said slider, an auxiliary bolt slidably mounted on said main bolt for movement in a direction transverse to the movement of the main bolt, a bar slidably mounted on said main bolt for longitudinal movement with respect thereto, a bell crank pivoted to said main bolt and having arms engaging said auxiliary bolt and said bar, and a second bell crank pivoted to said main bolt and having an arm engaging said bar, means on said second bell crank adapted to engage said slider, a rear cover plate on said casing provided with a slot, and said last mentioned means comprising a member rotatably mounted on said second bell crank and having an arm engaging within said slot and a bent back portion adapted to engage said slider.
4. In a lock, a casing, a main bolt slidably mounted therein, means for projecting said main bolt comprising a slider mounted on said main bolt for sliding movement in a direction transverse to the movement of said main bolt, a member rotatably mounted on said casing and having an arm pivoted to said slider, a pin on said slider, an auxiliary bolt slidably mounted on said main bolt for movement in a direction transverse to the movement of said main bolt, and means for moving said auxiliary bolt during movement of said main bolt, said means comprising a member on said main bolt and operatively connected to said auxiliary bolt and having a portion adapted to disengageably engage said pin.
5. In a lock, a casing, a main bolt slidably mounted therein, means for projecting said main bolt comprising a slider mounted on said main bolt for sliding movement in a direction transverse to the movement of said main bolt, a member rotatably mounted on said casing and having an arm pivoted to said slider, a pin on said slider, an auxiliary bolt slidably mounted on said main bolt for movement in a direction transverse to the movement of said main bolt, and means for moving said auxiliary bolt during movement of said main bolt, said means comprising a bell crank pivoted to said main bolt and operatively connected to said auxiliary bolt, a member rotatably mounted on said bell crank and having a portion adapted to disengageably engage said pin.
6. In a lock, a casing, a main bolt slidably mounted therein, means for projecting said main bolt, comprising a slider mounted on said main bolt for sliding movement in a direction transverse to the movement of said main bolt, a member rotatably mounted on said casing and having
- an arm pivoted to said slider, a pin fixed to said slider, an auxiliary bolt slidably mounted on said main bolt for movement in a direction transverse to the movement of said main bolt, and means for moving said auxiliary bolt during movement of said main bolt, said means comprising a bell crank pivoted to said main bolt and operatively connected to said auxiliary bolt, a member rotatably mounted on said bell crank and having a portion adapted to disengageably engage said pin, 10 and means fixed with respect to said casing for controlling the movement of said rotatable member.
7. In combination, a lock comprising a casing, a main bolt slidably mounted therein, means for projecting said main bolt, a pair of auxiliary bolts slidably mounted on the main bolt for movement in a direction transverse to the movement of the main bolt, a bar slidably mounted on said main bolt for longitudinal movement with respect thereto, and a pair of bell cranks pivoted to said main bolt on opposite sides of said bar, each having an arm engaging the bar and an arm engaging one of the auxiliary bolts, means for causing sliding movement of said bar during projection of said main bolt for moving said auxiliary bolts in opposite directions, said means comprising another bell crank pivoted to said main bolt and engaging said sliding bar, and means on said last mentioned bell crank coacting with said projecting means for rotating said last mentioned bell crank during a portion only of the projecting movement of said main bolt.
8. In combination, a lock comprising a casing, a main bolt slidably mounted therein, means for projecting said main bolt, a pair of auxiliary bolts slidably mounted on the main bolt for movement in a direction transverse to the movement of the main bolt, a bar slidably mounted on said main bolt for longitudinal movement with respect thereto, a pair of bell cranks pivoted to said main bolt on opposite sides of said bar each having an arm engaging the bar and an arm engaging one of the auxiliary bolts, means for causing sliding movement of said bar during projection of said main bolt for moving said auxiliary bolts in an opposite direction, said means comprising another bell crank pivoted to said main bolt and engaging said sliding bar, means on said last mentioned bell crank coacting with said projecting means for rotating said last mentioned bell crank during a portion only of the projecting movement of said main bolt, a rear cover plate on said casing, and means on said cover plate for controlling movement of said last mentioned bell crank.

CHARLES KEMP.
